(Continued)

Primary Examiner — Ricky Pham(74) *Attorney, Agent, or Firm* — McDermott Will & Emery LLP**CLAIM**

We claim the ornamental design for a rear surface of a chair back, as shown and described.

DESCRIPTION

FIG. 1 is a rear view of a rear surface of a chair back according to the new design. In the drawings, the broken lines form no part of the claimed design.

1 Claim, 1 Drawing Sheet# US D696,545 S
